PAUL MILLER, OF BRIDGEPORT, OHIO.

HEADLIGHT-DIMMER.

1,246,137.

Specification of Letters Patent. Patented Nov. 13, 1917.

Application filed May 14, 1917. Serial No. 168,377.

To all whom it may concern:

Be it known that I, PAUL MILLER, a citizen of the United States of America, and resident of Bridgeport, county of Belmont, 5 and State of Ohio, have invented certain new and useful Improvements in Headlight-Dimmers, of which the following is a specification.

This invention relates broadly to light-controlling devices, and more particularly to 10 an anti-glare attachment for headlights.

The primary object of the invention is to provide a comparatively inexpensive attachment for the headlights of automobiles and 15 the like whereby the light may be readily controlled either to permit the light to be projected forward in a practically unobstructed manner for effecting full illumination of the roadway for a long distance in 20 advance of the car, or to deflect downward the major portion of the light rays for eliminating the objectionable blinding glare, as when meeting another car or pedestrians in the roadway.

25 In describing the invention in detail, reference is herein had to the accompanying drawing, in which—

Figure 1 is a vertical sectional view of an automobile lamp, illustrating the invention 30 applied thereto and showing the vanes in their normal horizontally disposed position;

Fig. 2 is a similar section of the removable front portion, or door, of the lamp with the 35 vanes occupying inclined position;

Fig. 3 is a central horizontal section of the same;

Fig. 4 is a front elevation of the lamp as shown in Fig. 1;

Fig. 5 is an enlarged detail section showing the pivotal mounting of the vanes; and—

Fig. 6 is an enlarged detail section showing the pivotal connection of the shift bar with the vanes.

Referring to said drawings, in which like 45 designating characters distinguish like parts throughout the several views—

1 indicates the body of a headlight which may be of any appropriate or ordinary form having a lamp 2 mounted therein and having 50 a glass face 3 mounted in the removable front portion or door 4 thereof.

Fitted within the rim of the removable front portion or door 4 adjacent to the rear face of the glass 3 is the peripheral flange 5 of a circular one-piece frame 6 which is 55 preferably of hollow truncated-cone shape

and has its walls disposed adjacent and substantially parallel to the forward edge portion of the walls of the lamp body 1.

Disposed horizontally across the headlight 60 is a plurality of straight flat metal blades or vanes 15 arranged in two series 7 and 8, said vanes being preferably spaced at equidistant intervals for a purpose which will presently be explained. The vanes of the 65 upper series 7 which extend from the top of the headlight to a point approximately midway of the latter, are of uniform width, while the vanes of the lower series 8 uniformly decrease in width from the topmost 70 to the lowermost thereof, as shown. In a practical structure the vanes should probably be spaced about one-fourth inch apart, and the vanes of the upper series 7 would approximate one inch in width, while the 75 vanes of the lower series 8 would regularly decrease from said width to the lowermost vane which would approximate one-eighth inch in width.

The vanes are separately pivoted upon the 80 frame 6, each having a trunnion-like pin 9 fixed or formed on each end thereof adjacent to its front edge and disposed in alignment therewith, said pins being loosely fitted in or projecting through openings 10 85 provided therefor in said frame, as is most clearly shown in Fig. 5.

Loosely fitted in vertically aligned slots 11 provided in said vanes is an upright shift-rod 12 which occupies a position rearward 90 with respect to the pivot-pins 9. Each vane has a pin 13 crossing its slot 11 and passed loosely through a hole 14 provided therefor in said shift rod, said pins 13 having their opposite ends rigidly mounted upon the 95 vane, as by soldering. The lower end of said shift-rod projects outward through the lower part of the headlight and may be connected to any suitable mechanism (not shown) whereby it may be elevated or lowered and held in adjusted position.

It will be manifest from the foregoing description that the vanes may be shifted from a position wherein they lie horizontally to any desired inclined position, and vice versa, 105 by vertically shifting the position of the shift-bar. When disposed in horizontal position, as shown in Figs. 1 and 4, but little obstruction is presented by the vanes to the passage of the rays of light emanating from the lamp 2, and, consequently, practically maximum illumination of the roadway to a 110

long distance ahead of the car may be obtained with the vanes in said position. When, however, it becomes desirable to so dim or obstruct the light rays as to render them unobtrusive or prevent the glare, the shift-bar may be elevated for causing the vanes to assume an upwardly and rearwardly inclined position, as shown in Fig. 2. In the extreme upwardly inclined position, light rays, both direct and reflected, are prevented from passing between the upper series 7 of vanes either in an upward or in a horizontal direction by reason of the fact that the front edge of each vane of said series occupies a lower level than that of the rear edge of the next adjacent vane thereabove. In a mean inclined position, as the position shown in Fig. 2, a relatively small proportion of the rays are permitted to pass unobstructedly between the vanes of the series 7, and that only in a substantially horizontal direction.

Due to the relatively narrower width of the vanes in the lower series 8, a sharper inclination of said vanes is obviously required to intercept a large proportion of the light rays, said vanes permitting a relatively large volume of light to pass therebetween both in a horizontal and in upward directions until a very sharp inclination is assumed. It will of course be understood, moreover, that less light will be intercepted at any inclination by those vanes having least width.

It will be manifest that sufficient light for a fair degree of road illumination will be permitted to pass unobstructedly between the vanes of the lower series 8 when the vanes occupy an extreme inclined position wherein practically all of the light rays passing through the upper half of the headlight have first impinged upon and been deflected in a downward direction by the vanes of the upper series. Further, it will be obvious that, unless inclined to an extent less than 45°, practically all objectionable blinding glare will be thereby effectually obliterated.

Various modifications within the scope of the appended claims may be resorted to.

50 What is claimed is—

1. A light-controlling device for headlights, comprising a frame for mounting adjacent to the headlight glass, a plurality of horizontally disposed blades having their

ends pivoted on said frame, said blades being spaced at a substantially uniform distance apart and being arranged in two series, one series having the blades thereof of substantially uniform width and the second series having the blades thereof of different width from that of the blades of the first-mentioned series, and means connected to said blades whereby they may be swung to and from inclined positions.

2. A light-controlling device for headlights, comprising a frame for mounting adjacent to the headlight glass, a plurality of horizontally disposed blades having their ends pivoted on said frame, said blades being spaced at a substantially uniform distance apart and being arranged in two series, one series extending from the top of the headlight to an approximately midway point and having the blades thereof of substantially uniform width and the other series extending from said midway point to the bottom of the headlight and having the blades thereof gradually decreasing in width from the uppermost to the lowermost, and means for shifting said blades from a horizontal to inclined positions, and vice versa.

3. A light-controlling device for headlights, comprising a frame for mounting adjacent to the headlight glass, a plurality of horizontally disposed blades having their ends pivoted on said frame, said blades being arranged in two series, one series extending from the upper part of the headlight to an approximately midway point and having its blades of substantially uniform width, and the other series extending from said point to the lower part of the headlight and having its blades gradually decreased in width from the topmost to the lowermost thereof, and means connected to said blades whereby they may be shifted to and from inclined positions, the blades of the two series having a substantially uniform spacing with respect to each other so that when occupying inclined position the wider blades intercept and deflect light in larger volume than the narrower blades.

In testimony whereof, I affix my signature in presence of two subscribing witnesses.

PAUL MILLER.
